UNITED STATES PATENT OFFICE.

HUGO C. RASSMANN, OF BEAVER DAM, WISCONSIN, ASSIGNEE TO R. RASSMANN MFG. CO. INC., OF BEAVER DAM, WISCONSIN.

STALL CONSTRUCTION.

Application filed July 3, 1923. Serial No. 649,261.

This invention relates to improvements in stall constructions and more particularly to improved stanchion operating and controlling means,—one object of my present invention being to provide simple mechanism which will facilitate easy adjustment of the stanchion and operating means forwardly or backwardly to align the cattle with the gutter.

10 A further object is to provide improved latching means in the operating mechanism for a stanchion.

15 A further object is to provide, in stanchion operating mechanism, latching and stanchion opening and closing means which may be employed in the simultaneous operation of a plurality of stanchions but which will permit of any one or more of the stanchions being locked in closed position and all the 20 others opened simultaneously.

25 With these and other objects in view, the invention consists in certain novel features of construction and combinations of parts as hereinafter set forth and pointed out in the claims.

In the accompanying drawings,—

Figure 1 is a view in elevation showing an embodiment of my invention.

30 Figure 2 is an enlarged view partly broken away, showing the positions which the parts assume when a stanchion is open.

Figure 3 is a view partly in elevation and partly in section showing the positions of the parts when the stanchion is closed, and

35 Figure 4 is a sectional view on the line 4—4 of Figure 3.

In Figure 1 of the drawing I have shown three stall posts 1—1—1 representing two stalls 2—2, but it will of course be understood 40 that any desired number of stalls may be employed. The posts 1 support, through the medium of brackets 3, a rail 4 which is preferably angular in cross-section and said brackets are provided with upward extensions forming guides 5 for an operating rod 6. A stanchion 7 is provided for each stall and may comprise an upright member 8 having a rigid horizontal member 9 at its upper end and a rigid horizontal member 10 at its 45 lower end and a member 11 having pivotal or hinged connection at its lower end with the lower member 10. A slide 12 is mounted on the upper horizontal stanchion member 9 and has pivotally connected therewith a rod 13 which telescopes into the tubular

upper end portion of the hinged stanchion member 11. The lower end of each stanchion is connected as at 14 with a bottom bracket 15,—the construction being such as to permit adjustment of the bottom portion of the stanchion longitudinally of the stall and such construction may be substantially that fully shown and described in Patent No. 1,416,117 granted to me May 9, 1922. The upper horizontal bar 9 of the 60 stanchion has secured thereto a bracket 16 and this bracket carries a swivel 17 adjustably connected with a bracket 18 secured to the rail 4. The connection of the stanchion with the rail 4 through the medium of the bracket 18 is such as to permit adjustment of the upper portion of the stanchion longitudinally of the stall and the said adjustable connection may be such as fully shown and described in my former Patent No. 70 1,404,057 granted January 17, 1922.

A slide 19 is mounted on the supporting rail and also has connected therewith, by means of bolts 20, a clamp 21 secured to the operating rod or bar 6. The slide 19 carries the opening and closing mechanism for the stanchion, and by providing the guides 5 for the operating rod, binding of the slide 19 connected with said operating rod, on the rail 4 will be prevented should the animal 80 crowd in the stall and tend to cause twisting of the slide.

The slide comprises two members and the lower member 22 of said slide may be made an integral part of a slide bracket 23. This bracket is elongated in shape and includes a plurality of spaced depending arms or projections 24 between any two of which, a latch yoke 25 may be pivotally supported by a removable pin 26 passing through suitable 90 aligning holes in said depending arms or projections. The pivot pin 26 is provided at one end with an arm 27 to be disposed in an open notch or recess 28 formed by an arm 29 at one end of the bracket 23, and 95 said arm 29 is made with a slot 30 open at one end. By connecting the latch yoke 25 with the slide bracket as above explained, 100 said yoke may be readily adjusted longitudinally of the stall when the stanchion is adjusted to align a particular animal with the gutter. The pivot pin 26 will be held normally against displacement by reason of the normal position of the arm 27 of the 105 pin in the recess 28, out of alignment with 110

the open slot 30, but when it becomes necessary to effect adjustment of the latch, the pin 26 will be turned to align the arm 27 with the slot 30 and then withdraw said pin 5 to permit the latch yoke to be adjusted. The pivot pin may then be adjusted.

The latch yoke 25 projects over the slide 12 with which the hinged member 11 of the stanchion is connected and is provided with 10 a wide end portion 25^a having a curved slot 25^b which receives a pin 31 projecting from the stanchion slide 12,—such pin and slot connection permitting limited turning movement of the stanchion without danger of the 15 yoke becoming disengaged from the pin 31. When the parts are in these positions (as shown in Figures 3 and 4) the stanchion will be in its closed latched position and will be retained in such position by reason of 20 the construction and arrangement of the mechanism employed for controlling the operation of the stanchion opening and closing devices. This mechanism includes a slotted hand lever 32 mounted on a pin 33 supported 25 by a bracket 34 on the stall post 1 at one end of the series of stalls. An arm or crank 35 (disposed normally at right angles to said lever) is also mounted on the pin 33 and provided with a notch 36 to be engaged by a 30 lug 36^a on the lever. A rod 37 is pivotally connected at one end with the arm or crank 35 and at its other end this rod is pivotally connected with the operating rod or bar 6. It is evident that when the arm or crank 35 35 is in the position as shown in Figure 1, the slide bracket 23 will be prevented from moving and hence the stanchion will be held in closed position. By moving the hand lever 32 upwardly to engage the lug 36^a in 40 the notch 36 in the arm or crank 35 and then raising said hand lever, motion will be imparted, through the medium of the crank arm 35, rod 37 and operating rod or bar 6 to the slide brackets 23 and thus effect the 45 opening of the stanchions, and a reverse operation of the hand lever will cause the stanchions to be closed. After the lever shall have been operated to open the stanchions, it may be disengaged from the crank 50 arm and permitted or be made to depend from the pin 33.

The pivoting of the latch yoke to the slide bracket will cause it to accommodate any vertical movements of the stanchion caused 55 by movements of the animal but in order to prevent possibility of accidental disengagement of the latch yoke 25 from the pin 31, I provide the yoke with upwardly projecting stop lugs 38 disposed under a depending 60 stop plate 39 pivotally supported by the slide bracket 23. The pivot pin 40 to which the stop plate is secured, is provided at one end with an arm 41 to permit the operator to turn said pin and raise the stop plate 39 65 for a purpose hereinafter explained. The

latch yoke is provided rearwardly of its pivotal support, with a toe 42 which is normally engaged by a pivotally supported depending stop plate 43, the latter being carried by the slide bracket 23 and its pivot 70 pin 44 being provided with an arm 45 to permit said stop plate to be readily manipulated.

Should all the stanchions of the series be connected, through the latch yokes, with the 75 several slide brackets, in the manner shown in Figures 3 and 4 and at the left of Figure 1, manipulation of the hand lever 32 would cause all the stanchions to be opened simultaneously and reverse movement of said lever would cause them all to be closed simultaneously. It sometimes happens however, that it is desired to retain one or more animals in its stall and to release all the others. In such case, it will be necessary 80 to raise the latch yoke for the stanchion which is to remain closed so as to disconnect said latch yoke from its hinged stanchion member and thus prevent this particular stanchion from being opened when the 85 others are opened. Before the latch can be raised sufficiently to free it from the pin 31, the stop plate 39 must first be raised. When the latch yoke shall have been released from the pin 31, the stop plate 43 will become 90 disengaged over the toe 42 of the latch yoke and retain the latter in the raised position indicated at the right of Figure 1. The latch yoke having been disconnected from the hinged member of the stanchion, the stanchion although closed, will be unlocked. It is important however, that it be locked in 95 closed position, and to accomplish this, an approximately U-shaped lock bolt 46 is mounted on each stanchion bracket 16 and 100 maintained normally in idle position by means of a spring 47. The slide 12 with which the hinged member is connected is provided at its sides with sockets 48 and when the stanchion is to be locked with the 105 use of the lock bolt 46, said bolt will be thrown over from the position shown in Figure 4 and at the left of Figure 1 and caused to engage in one of the sockets 48 in the slide 12 as indicated at the right of 110 Figure 1. The reason for providing two diametrically opposite sockets 48 is that it is sometimes desirable to dispose the lock bolt 46 opposite to the position shown in 115 the drawings.

With my improvements, the stanchions may be readily manipulated and easily adjusted to align the animals relatively to the stall gutter.

Various changes might be made in the 125 details of construction without departing from the spirit of my invention or limiting its scope and hence I do not restrict myself to the precise details herein set forth.

Having fully described my invention 130

what I claim as new and desire to secure by Letters Patent, is:

1. The combination with a stall frame including a top rail, a stanchion having a hinged member, and adjustable supporting devices for said stanchion, of a slide bracket mounted on said rail, a latch yoke cooperable with the hinged member of the stanchion, said slide bracket having a plurality of points of attachment for said latch yoke, whereby the connection of the latter with the slide bracket may be adjusted longitudinally of the stall when the stanchion is so adjusted, and operating means connected with said slide bracket.

2. The combination with a stall frame including a top rail, a stanchion including a hinged member, and means for supporting said stanchion from the top rail, of a slide bracket mounted on the top rail, a latch yoke pivotally mounted upon said slide bracket and removably engaged with the hinged member of the stanchion, means carried by the slide bracket to maintain the yoke in engagement with the hinged stanchion member, and operating means for said slide bracket.

3. The combination with a stall frame including a top rail, and a stanchion supported from said top rail and comprising relatively movable members, of a slide on one stanchion member and connected with the other stanchion member, a pin projecting from said slide, a slide bracket mounted on the top rail, a latch yoke having pivotal connection with said slide bracket and provided with a transversely elongated slot receiving the pin on the slide on the stanchion member, stop devices on the slide bracket normally preventing disengagement of the yoke from said pin, and manually operable means for said slide bracket.

4. The combination with a stall frame including a top rail, and a stanchion supported from said rail and comprising relatively movable members, of a slide mounted on one stanchion member and having pivotal and sliding connection with the other stanchion member, a pin on said slide, a slide bracket mounted on said top rail, a latch yoke pivoted to said slide bracket and removably engaging said pin, stop means carried by the slide bracket operable normally to prevent disengagement of the yoke from said pin, an operating rod connected with said slide bracket, guides for said operating rod, a hand lever, a crank operable by said hand lever, and a connection between said crank and the operating rod.

5. The combination with a stall frame including a top rail, a stanchion comprising a member having a vertical portion and horizontal arms at respective ends thereof and a member hinged to the lower horizontal arm, and means for supporting said stanchion from the top rail, of a slide bracket mounted on said top rail, a latch yoke pivoted to the slide bracket and having an opening to receive said pin, means on the slide bracket operable normally to prevent disengagement of the yoke from said pin, and operating means for said slide bracket.

6. The combination with a stall frame including a top rail, and a stanchion supported from said rail and comprising relatively movable members, of a slide on one stanchion member and connected with the other stanchion member, a pin on said slide, a slide bracket, a yoke pivotally connected with said slide bracket and removably engaging said pin, operating means for the slide bracket, means for supporting said yoke out of engagement with said pin, and a bolt mounted on one of said stanchion members and adapted to be made to engage the slide connected with the other stanchion member when the yoke is disengaged from said pin.

7. The combination with a stall frame including a top rail, and a plurality of stanchions supported from said rail, each stanchion comprising relatively movable members, of a slide mounted on one stanchion member of each stanchion and connected with the other member thereof, a pin on each slide, slide brackets mounted on the top rail over the respective stanchions, a yoke pivotally mounted in each slide bracket and cooperable with the pin of the slide on the adjacent stanchion, a toe on each yoke, a hinged member on each slide bracket to engage over said toe when the yoke is disengaged from the pin of the slide on the adjacent stanchion, a bolt mounted on one member of each stanchion and adapted to be made to engage the slide connected with the other member thereof, an operating rod connected with all the slide brackets, and means for moving said operating rod to move the slide brackets simultaneously.

8. The combination with a stanchion frame including a top rail, a stanchion comprising relatively movable members, adjustable supporting means between the stanchion and the top rail, and adjustable means for the lower end of the stanchion, of an elongated slide bracket mounted on the top rail and disposed at right angles thereto, said slide bracket having a plurality of parallel, perforated arms, a yoke adapted to enter between any two of said arms, a removable pivot pin passing through said arms and said yoke to pivotally support the latter, said yoke having an opening, a slide on one member of the stanchion and connected with the other member thereof, a pin on said slide to enter the opening in the pivoted yoke, and operating means connected with

115
120
125
130

said slide bracket to move the same on the top rail for effecting the opening or closing of the stanchion.

9. The combination with a stall frame including a top rail, a stanchion including a hinged member, and means for supporting the stanchion from the top rail, of a slide bracket mounted on the top rail, a latch yoke pivoted upon the slide bracket and detachably engaged with the hinged member of the stanchion, means for moving the slide bracket along the top rail, and a gravity-controlled member hung on the slide bracket above and in the path of pivotal movement of the latch yoke whereby to normally hold said yoke in engagement with the hinged member of the stanchion.
10. The combination with a stall frame

including a top rail, a stanchion including a hinged member, and means for supporting the stanchion from the top rail, of a slide bracket mounted on the top rail, a latch yoke pivoted upon the slide bracket and detachably engaged with the hinged member of the stanchion, means on the slide bracket normally holding the latch yoke in engagement with the hinged member of the stanchion, means on the slide bracket operable to hold the yoke out of engagement with the hinged stanchion member, and means for moving the slide bracket along the top rail.

In testimony whereof, I have signed this specification.

HUGO C. RASSMANN.

Certificate of Correction.

It is hereby certified that the name of the assignee in Letters Patent No. 1,594,300, granted July 27, 1926, upon the application of Hugo C. Rassmann, of Beaver Dam, Wisconsin, for an improvement in "Stall Constructions," were erroneously written and printed "R. Rassmann Mfg. Co. Inc.," whereas said name should have been written and printed as *F. Rassmann Mfg. Co., Inc.*, as shown by the records of assignments in this office; and that the said Letters Patent should be read with this correction therein that the same may conform to the record of the case in the Patent Office.

Signed and sealed this 24th day of August, A. D. 1926.
[SEAL.]

M. J. MOORE,
Acting Commissioner of Patents.
